UNITED STATES PATENT OFFICE.

CHARLES C. KROUSE, OF WILLIAMSPORT, PENNSYLVANIA.

DESIGN FOR A BUCKLE.

SPECIFICATION forming part of Design No. 23,721, dated October 23, 1894.

Application filed September 18, 1894. Serial No. 523,418. Term of patent 14 years.

To all whom it may concern:

Be it known that I, CHARLES C. KROUSE, a citizen of the United States, residing at Williamsport, in the county of Lycoming and State of Pennsylvania, have invented and produced a new and original Design for Back-Band Buckles, of which the following is a specification, reference being had to the accompanying drawings, in which—

10 Figure 1—shows a plan or face view of the buckle, and Fig. 2— a side elevation, these views being deemed necessary to fully illustrate my design.

15 The features of my design consist of slotted loops 1 and 2, of a base plate A (the ends of

which loops project beyond the intermediate plate 3 of said base), and a hook 6 on the lower edge of the loop 2, together with a clamp 4, having a tongue 5, which meets the end of the hook 6, and is bent down to bear on the 20 lower loop.

I claim—

The design for a buckle, substantially as herein shown.

In testimony whereof I affix my signature in 25 presence of two witnesses.

CHARLES C. KROUSE.

Witnesses:

HENRY E. COOPER,
MARGARET V. COOPER.
